(57) **CLAIM**

The ornamental design of an apparatus for grilling skewered food, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a back elevation view of an apparatus for grilling skewered food;

FIG. 2 is a bottom plan view thereof;

FIG. 3 is a front elevation view with a grip pulled thereof;

FIG. 4 is a front elevation view without the grip thereof;

FIG. 5 is a left-side elevation view thereof;

FIG. 6 is a top plan view thereof;

FIG. 7 is a right-side elevation view thereof; and,

FIG. 8 is a perspective view.

The broken lines depict portions of the apparatus that form no part of the claimed design.
